UNITED STATES PATENT OFFICE

134,986

DESIGN FOR A TOILET SEAT HINGE

William D. Schultz, Dolgeville, N. Y., assignor to Julius Breckwoldt & Son, Inc., Dolgeville, N. Y.

Application September 7, 1942, Serial No. 108,147

Term of patent 3½ years

To all whom it may concern:

Be it known that I, William D. Schultz, a citizen of the United States and a resident of Dolgeville, in the county of Herkimer and State of New York, have invented a new, original, and ornamental Design for a Toilet Seat Hinge, of which the following is a specification, reference being had to the accompanying drawing, forming part thereof.

Fig. 1 is a perspective view of a toilet seat hinge showing my new design.

Fig. 2 is a front elevational view thereof.

I claim:

The ornamental design for a toilet seat hinge, as shown.

WILLIAM D. SCHULTZ.
